DESIGN FOR A RADIATOR GRILLE COVER FOR AUTOMOBILES

Willard L. Morrison, Lake Forest, Ill.

Application October 8, 1936, Serial No. 65,208

Term of patent 7 years

To all whom it may concern:

Be it known that I, Willard L. Morrison, a citizen of the United States, residing at Lake Forest, in the county of Lake and State of Illinois, have invented a new, original, and ornamental Design for a Radiator Grille Cover for Automobiles, of which the following is a specification, reference being had to the accompanying drawing, forming part thereof.

Fig. 1 is a perspective view of the radiator grille cover on a smaller scale than the other figures and wherein the shutters are shown in open position;

Fig. 2 is a front elevational view of the device;
Fig. 3 is a side elevational view of the device;
Fig. 4 is a sectional view taken on line 4—4 of
Fig. 3.

The characteristic feature of the present design is that a uniform horizontal section conforms substantially to the arc of a circle and a uniform vertical section is a straight line.

I claim:

The ornamental design for a radiator grille cover for automobiles, substantially as shown and described.

WILLARD L. MORRISON.
